FIG. 3 is a second side view of the screwdriver of FIG. 1.

FIG. 4 is a front side view of the screwdriver of FIG. 1.

FIG. 5 is a back side view of the screwdriver of FIG. 1.

FIG. 6 is a third side view of the screwdriver of FIG. 1.

FIG. 7 is a fourth side view of the screwdriver of FIG. 1.

FIG. 8 is a perspective view of a second embodiment of the screwdriver.

FIG. 9 is a first side view of the screwdriver of FIG. 8.

FIG. 10 is a second side view of the screwdriver of FIG. 8.

FIG. 11 is a front side view of the screwdriver of FIG. 8.

FIG. 12 is a back side view of the screwdriver of FIG. 8.

FIG. 13 is a third side view of the screwdriver of FIG. 8.

FIG. 14 is a fourth side view of the screwdriver of FIG. 8.

FIG. 15 is a perspective view of a third embodiment of the screwdriver.

FIG. 16 is a first side view of the screwdriver of FIG. 15.

FIG. 17 is a second side view of the screwdriver of FIG. 15.

FIG. 18 is a front side view of the screwdriver of FIG. 15.

FIG. 19 is a back side view of the screwdriver of FIG. 15.

FIG. 20 is a third side view of the screwdriver of FIG. 15.

FIG. 21 is a fourth side view of the screwdriver of FIG. 15.

FIG. 22 is another perspective view of the first embodiment of the screwdriver, wherein the screwdriver is illustrated using wireframe drawing technique.

FIG. 23 is a first side view of the screwdriver of FIG. 22.

FIG. 24 is a second side view of the screwdriver of FIG. 22.

FIG. 25 is a front side view of the screwdriver of FIG. 22.

FIG. 26 is a back side view of the screwdriver of FIG. 22.

FIG. 27 is a third side view of the screwdriver of FIG. 22.

FIG. 28 is a fourth side view of the screwdriver of FIG. 22.

FIG. 29 is another perspective view of the second embodiment of the screwdriver wherein the screwdriver is illustrated using wireframe drawing technique.

FIG. 30 is a first side view of the screwdriver of FIG. 29.

FIG. 31 is a second side view of the screwdriver of FIG. 29.

FIG. 32 is a front side view of the screwdriver of FIG. 29.

FIG. 33 is a back side view of the screwdriver of FIG. 29.

FIG. 34 is a third side view of the screwdriver of FIG. 29.

FIG. 35 is a fourth side view of the screwdriver of FIG. 29.

FIG. 36 is another perspective view of the third embodiment of the screwdriver wherein the screwdriver is illustrated using wireframe drawing technique.

FIG. 37 is a first side view of the screwdriver of FIG. 36.

FIG. 38 is a second side view of the screwdriver of FIG. 36.

FIG. 39 is a front side view of the screwdriver of FIG. 36.

FIG. 40 is a back side view of the screwdriver of FIG. 36.

FIG. 41 is a third side view of the screwdriver of FIG. 36;

and,

FIG. 42 is a fourth side view of the screwdriver of FIG. 36.
